Application March 19, 1945, Serial No. 118,566

Term of patent 14 years

(Cl. D49—6)

To all whom it may concern:

Be it known that we, Andrew H. Gerhardt and Arthur P. Schulz, citizens of the United States, residing respectively at Skokie and Hinsdale, in the counties of Cook and Du Page and State of Illinois, have invented a new, original, and ornamental Design for a Combined Ironing Machine and Stand, of which the following is a specification, reference being had to the accompanying drawing, forming a part thereof.

In the drawing:

Fig. 1 is a perspective view showing the front and one end of a combined ironing machine and stand embodying our new design.

Fig. 2 is a rear elevational view thereof.

Fig. 3 is an end elevational view thereof.

We claim:

The ornamental design for a combined ironing machine and stand, substantially as shown.

ANDREW H. GERHARDT.

ARTHUR P. SCHULZ.
